(57) CLAIM

The ornamental design for the pump inlet flow strainer, as shown and described herein.

DESCRIPTION

FIG. 1 is a perspective view from the drive side of the pump inlet flow strainer design of the present invention;

FIG. 2 is a plan view of the pump inlet flow strainer article looking into the drive side opening in the pump inlet flow strainer;

FIG. 3 is a view in elevation of the pump inlet flow strainer with the drive side of the pump inlet flow strainer being oriented upwardly;

FIG. 4 is a perspective view of the pump inlet flow strainer as seen from the suction side of the pump inlet flow strainer; and, FIG. 5 is a plan view of the pump inlet flow strainer as viewed looking into the suction side of the pump inlet flow strainer. The broken lines shown in FIGS. 1, 2, 4 and 5 form no part of the claimed design.
